INTERLOCKING RELAY

Frederick T. Fereday, Louisville, Ky.

Application July 19, 1939, Serial No. 285,448

8 Claims. (Cl. 200—98)

This invention relates to interlocking relays such as are used for the control of highway crossing signals, and has generally in view to provide an interlocking relay embodying an interlocking mechanism having various improved features as compared with the interlocking mechanisms of known interlocking relays.

An interlocking relay is simply two ordinary neutral relays which an interlocking mechanism therebetween, whereby the operation of each is affected by the operation of the other to the end that proper control of flashing lamps, bells, wigwag signals, stop signs, gate lamps, automatic crossing gates and the like is effected. Heretofore, such relays have caused considerable trouble because of failure, for one reason or another, of their interlocking mechanisms. The construction of some mechanisms is such that their successful operation is dependent upon overcoming considerable friction. Such mechanisms sometimes fail because of excessive friction. Other mechanisms are frail and soon wear, bend or break in service with consequent failures. Still other mechanisms are very intricate and require very delicate adjustments which are difficult to maintain in service, with the consequence that they frequently fail due to loss of adjustment of their parts.

Accordingly, the present invention has more particularly in view to provide an interlocking relay embodying an interlocking mechanism which is of simple, strong, sturdy and durable construction and which, in operation, is subjected to very little friction, whereby it is unlikely to fail in service due to causes as enumerated which have resulted in failures of prior interlocking mechanisms. In short, the primary object of the present invention is to provide an interlocking relay which remains thoroughly reliable and efficient in operation over long periods of time without attention.

Another object of the present invention is to provide an interlocking mechanism embodying novel adjustment means which are easy to adjust and which reliably maintain their adjustments.

With the foregoing and other objects in view, which will become more fully apparent as the nature of the invention is better understood, the same consists in the novel features of construction, combination and arrangement of parts as will be hereinafter more fully described, illustrated in the accompanying drawings and defined in the appended claims.

In the accompanying drawings, wherein like

characters of reference denote corresponding parts in the different views:

Figure 1 is a diagrammatic view illustrating a simple relay installation for the control of a lamp flashing mechanism.

Figure 2 is a longitudinal section through an interlocking relay constructed in accordance with one practical embodiment of the invention.

Figure 3 is a transverse section through the relay shown in Fig. 2.

Figure 4 is an enlarged section through one of the switch arms of the relay shown in Figs. 2 and 3.

Figure 5 is an enlarged section through the mounting means for one of the locking arms of the interlocking mechanism of the relay shown in Figs. 2 and 3.

Figure 6 is a section on the line 6—6 of Fig. 5.

Figures 7 through 11 are front elevations of the present interlocking mechanism illustrating different operative positions of the locking arms and the locking dogs of said mechanism; and

Figure 12 is a perspective view of the mounting means for the locking dogs of the present interlocking mechanism.

Referring to the drawings in detail, first with particular reference to the explanatory installation illustrated in Fig. 1, A designates a railroad track which is divided, by insulated rail joints 1 at a highway crossing and by other insulated rail joints 2, 2 spaced to either side of said joints 1, into a pair of insulated track sections, a, a disposed, respectively, at opposite sides of the highway crossing.

Across the end of each track section a remote from the highway crossing is connected a track battery 3, while across the end of each track section at or near the highway crossing is connected a relay R.

Each relay R includes an electro-magnet 4, an associated armature 5 and a back contact 6. Both armatures and both back contacts are included in the circuit of flasher relay F which controls the flashing of a pair of lamps 7.

Normally the electro-magnets 4 are energized due to same being in closed circuit through the track sections a, a with the track batteries 3. Therefore, the armatures 5 normally are picked up and are in open circuit relationship to the back contacts 6. Consequently, the circuit of the flasher relay F normally is open and the lamps 7 normally are inoperative. When, however, a train enters either of the track sections a it shunts the relay R connected with that track section. Thereupon the armature of the shunted

relay drops and engages its related back contact 6, thereby closing the circuit of the flasher relay F with the result that the lamps 7 are alternately flashed.

According to the Fig. 1 illustration, a train, after passing through one of the track sections a and upon entering the other track section, will shunt the relay related to the latter track section and thereby cause the circuit of the flasher relay F to remain closed even after the train has passed the grade crossing. This is undesirable and is a primary reason why an interlocking mechanism is used between two relays such as the relays R, R; viz., to assure that a train approaching a highway crossing in either direction will cause the flasher relay to operate, but will not maintain said relay in operation after the train has passed the highway crossing.

Referring now to Figs. 2 to 12 of the drawings which, as aforesaid, illustrate an interlocking relay embodying an interlocking mechanism constructed in accordance with the present invention, 10 designates a horizontally disposed panel of insulating material having mounted thereon, 15 in side to side relationship, two relays R, R corresponding to the relays R, R illustrated in Fig. 1 of the drawings. Each of these relays includes, as in the case of the relays illustrated in Fig. 1, an electro-magnet 4, an associated armature 5 and 20 any desired number of back contacts 6, depending upon the number of flasher relays or other signals or devices that are to be controlled.

The electro-magnets 4 are mounted on top of the panel 10 near the rear thereof and have pole pieces 11 which extend through said panel and are exposed at the under side thereof. The armatures 5 underlie the pole pieces 11 and at their rears are pivoted as indicated at 12, whereby they are upwardly swingable by energization of the 25 magnets 4 and are free to drop under the influence of gravity when the magnets 4 are deenergized.

Fastened to each armature 5 are blocks 13 of insulating material carrying any desired number 30 of forwardly extending switch arms 14 for cooperation with any desired number of back contacts 6 suitably mounted on the panel 10 and disposed, of course, at the under side thereof. When the magnets 4 are energized and the armatures 5 are 35 lifted the switch arms 14 are spaced above the back contacts 6. When, however, the magnets 4 are deenergized and their armatures drop, the switch arms 14 engage the back contacts 6. If desired, front contacts 15 may be provided to be 40 engaged by the switch arms 14 when the armatures 5 are lifted, and said front contacts, in conjunction with said switch arms, may be used for the control of any desired circuits. Moreover, while the switch arms 14 may be of any suitable 45 construction, they preferably are of the known construction illustrated in Fig. 4 for yieldable cooperation with the back contacts 6 and also for yieldable cooperation with the front contacts 15 if the latter are employed.

60 The switch arms 14 and the back contacts 6 are suitably connected to binding posts 16 and 17, respectively, mounted on the panel 10 at the top thereof whereby they are readily connectible, through the instrumentality of said binding posts, with a flasher relay or the like to be controlled. Similarly, if front contacts are provided, they may be suitably connected with other binding posts 18 mounted on the panel 10 at the top thereof for convenience in connecting said 65 front contacts with desired devices to be controlled.

Other binding posts 19 are provided on top of the panel 10 for the connection of track circuit conductors with the electro-magnets 4.

Suitably secured to the panel 10 at the under side thereof, between the relays R, R, is a bracket 20 of inverted U-shape including a pair of depending, forwardly and rearwardly spaced legs 21 between which extend a pair of horizontally disposed, laterally spaced, forwardly and rearwardly extending pintles 22 which, at their ends, 10 are journaled in said legs.

The bracket 20 may be of one-piece or of any other suitable construction. Preferably, however, the legs 21 are separate from and are detachably connected with a top, block-like portion 23 of said bracket to facilitate mounting of the pintles 22 between said legs 21. In the present instance the upper, inner portions of the legs 21 are channeled to accommodate the end portions of the top, block-like portion 23 and 20 screws 24 are employed to fasten said legs to the ends of said block-like portion 23. Thereby the legs 21 are detachably connected with the block-like top portion 23 and, when connected thereto, are held rigidly in assembly therewith. A screw 25 passing downwardly through the panel 10 into the block-like top portion 23 serves to fasten the bracket 20 to said panel, while a polygonally-shaped lug 26 at the top of the block-like portion seated in a polygonally shaped recess in the under side of the panel 10 serves to hold said bracket against rotation relative to said panel.

Mounted on each pintle 22 is a locking dog 27, one related to one of the relays R and the other to the other of said relays. These locking dogs are right and left hand duplicates of each other and each includes a substantially vertically disposed leg 28 depending from the pintle 22, a substantially horizontally disposed arm 29 extending outwardly from the pintle 22 and weighted as indicated at 30, and a substantially horizontally disposed toe 31 extending outwardly from the lower end of the leg 28 and provided at its top, in spaced relationship to the leg 28, with an upwardly directed nib 32.

The locking dogs 27, under the influence of their weighted arms 29, tend constantly to swing inwardly or toward one another, and, unless restrained against such swinging movement, assume what may be termed neutral positions, as 45 illustrated in Fig. 11 of the drawings with their legs 28 disposed substantially vertically and in contact with each other at their inner or adjacent edges. On the other hand, if either dog is held with its leg 28 in an outwardly swung position and the other dog is unrestrained against swinging movement under the influence of its weighted arm 29, the latter dog assumes a position with its leg 28 disposed inwardly of its neutral position and against the leg of the other dog, 60 as illustrated for example, in Figs. 8 and 9 of the drawings.

If desired, resilient means may be associated with the dogs 27 to assist the weighted arms 29 in swinging said dogs and to impart thereto quick 65 swinging actions. For example, a light, expansion coil spring 33 may be interposed between the arms 29 above the pintles 22. However, resilient means for the purpose stated is not essential, as the weights 30, if sufficiently heavy, may be relied upon to impart all necessary and quick swinging movements to the dogs 27. Alternatively, resilient means such as the spring 33 may be used in lieu of the weights 30 to swing the locking dogs toward each other.

Extending forwardly from the armatures 5 of the relays R, R are locking arms 34, 34, respectively, one related to one of the locking dogs 27 and the other to the other of said locking dogs. The forward end portion of each locking arm 34 is disposed outwardly with respect to the leg 28 and in underlying relationship to the weighted arm 29 of its related locking dog 27, and the upper edge of the said forward end portion of each locking arm is disposed to engage the lower edge of the arm 29 of its related locking dog and to swing said dog outwardly from its neutral position when the related armature 5 is lifted responsive to energization of its related electro-magnet 4. Moreover, the toe 31 of each locking dog 27 is of such length that it underlies the lower edge of the forward end portion of the related locking arm 34 when the locking dog is swung outwardly responsive to lifting of the related armature 5, but is disposed inwardly with respect to the lower edge of the said forward end portion of the related locking arm 34 when the locking dog 27 is swung inwardly to or beyond its neutral position. Furthermore, the lower edge of the forward end portion of each locking arm 34 is disposed so that it is spaced above the toe 31 of its related locking dog 27 when the locking arm is elevated responsive to lifting of its related armature 5, this spacing being sufficiently great so that upon dropping of the arm 34 the locking dog 27 is permitted time within which to swing inwardly far enough to remove its toe 31 from beneath the locking arm 34 prior to the lower edge of the forward end portion of the locking arm reaching said toe 31. Accordingly, when either locking arm 34 drops and assuming lack of interference with inward swinging movement of the related locking dog 27 to or beyond its neutral position, the toe 31 of the locking dog does not interfere with dropping of the locking arm 34 sufficiently to permit the switch arms 14 to engage the back contacts 6. On the other hand, the spacing of the lower edge of the forward end portion of each locking arm 34 from its related toe 31 when the locking arm is elevated and the locking dog is in an outwardly swung position, is sufficiently small so that if the locking arm drops and the related locking dog 27 is not swung inwardly, the locking arm is intercepted in its downward movement by the locking dog toe 31 prior to the switch arms 14 engaging the back contacts 6.

Normally, both relays R, R are energized, as aforesaid. Accordingly, both armatures 5 normally are lifted and both locking arms 34 normally are elevated. Consequently, both locking dogs 27 normally are held in outwardly swung positions as illustrated in Figs. 2 and 7 of the drawings. If under such conditions, a train enters either track section a with consequent shunting of the related relay R, the armature 5 of that relay drops, carrying with it the related locking arm 34. As the locking arm 34 drops it releases the related locking dog 27 for inward swinging movement, and since such movement of said dog is unrestrained, it swings quickly inwardly under the influence of its weighted arm 29 and under the influence of the spring 33 if the latter or an equivalent thereof is used, coming to a position of rest against the other locking dog 27 as illustrated in Fig. 8 of the drawings. Inward swinging movement of the said locking dog occurs so quickly that its toe 31 is removed from the path of downward movement of the locking arm 34 prior to the lower edge of the locking arm

reaching the position formerly occupied by said toe. Accordingly, since the armature 5 is not limited in its downward movement by engagement of the locking arm 34 with the toe 31, said armature continues to drop until its switch arms 14 engage the back contacts 6, thereby closing whatever signal or other circuit that is controlled by the cooperation of said switch arms with said back contacts 6.

As the train progresses through the first mentioned track section a and enters the second track section, the other relay R is shunted from the battery circuit of the latter track section and its armature 5 drops. Since, however, the first mentioned locking dog 27 then is in an inwardly swung position, it restrains the other locking dog against inward swinging movement. Consequently, when the armature of the second mentioned relay R drops, its locking arm 34 is intercepted by the toe 31 of the second mentioned locking dog 27 before said armature has dropped sufficiently to engage its switch arms 14 with their related back contacts. The relationship of the locking dogs and locking arms then is as illustrated in Fig. 9. When the second mentioned locking arm 34 is resting upon the toe of the second mentioned locking dog 27 the nib 32 at the end of said toe is disposed outwardly of said locking arm. Consequently, as long as the second mentioned locking arm remains at rest upon the toe of its related locking dog, said dog cannot swing inwardly even though the first mentioned locking dog subsequently is swung outwardly. Thus, entering of the second track section a by the train does not result in engagement of the switch arms 14 with the back contacts 6 of the relay R related to the second track section.

When the train finally progresses entirely through the first mentioned track section a the normal or original status of the first mentioned relay R is restored. In other words, said first mentioned relay again is energized and its armature 5 and locking arm 34 are lifted, resulting in opening of the flasher relay or other controlled circuit and in restoration of the first mentioned locking dog 27 to its normal or original position as shown in Fig. 10.

As long as the train remains in the second mentioned track section the locking arm 34 of the related relay R remains resting upon the toe 31 of the locking dog 27 of the relay R related to the second mentioned track section. Thus, operation of the flasher or other signal device ceases upon movement of the train from the first track section a into the second track section a.

When finally the train leaves the second track section a the normal or original status of the relay R related to that track section is restored. Accordingly, following passage of a train through both track sections a, a the original status of the mechanism is restored in readiness to have the recounted operations repeated upon an approaching train moving into and through either track section and subsequently into and through the other track section.

Obviously, any interruption in the circuit of either track section a will result in closing of the flasher relay or other signal or similar circuit. Obviously, too, in the event of simultaneous interruption of the circuits of both track sections, both of the locking dogs 27 will swing to positions as shown in Fig. 11 of the drawings, with the result that all of the switch arms 14

will engage their related back contacts and assure closing of the flasher relay or other signal or similar circuit.

An important feature of the present invention resides in the provision of means for mounting the locking arms 34 on the armatures 5 for vertical adjustments relative thereto to accurately position their forward end portions relative to the locking dogs 27, thereby to insure proper cooperation of said locking arms with said locking dogs and proper cooperation of the switch arms 14 with the back contacts 6 and with the front contacts 15 if the latter are used. In the present instance one of the insulating blocks 13 of each armature 5 extends beyond the inner end of its related armature and has adjustably mounted thereon the related locking arm 34.

A longitudinally slotted metal block 35 is disposed against the under side of the projecting portion of each block 13, transversely thereof, and is securely clamped against the block 13 by a pair of yoke elements 36, 36. The yoke elements 36, 36 are of substantially inverted L-shape and include horizontal and vertical arms 37 and 38, respectively, the former of which overlie the related block 13 and the latter of which extend downwardly across the front and the rear edges of the block 13, respectively. The arms 38 are slotted, as indicated at 39, and accommodate the ends of the block 35 which project beyond the forward and the rear edges of the block 13. In the bottom of the block 35 are transverse channels 40 which accommodate bottom, transverse portions 41 of the arms 38, whereby said arms 38 are interlocked with the block 35. The arms 37 are provided with upstanding ears 42 that are connected together by a clamp screw 43. When the screw 43 is tightened its tendency is to rock the yoke elements 36, 36 upwardly, which results in the block 35 being clamped securely against the under side of the block 13.

The rear end portion of each locking arm 34 extends into the slot of its related block 35 and at its upper edge is provided with a notch 44 wherein is disposed a fulcrum pin 45 which is carried by and extends transversely of the block 35 at a point approximately midway between the ends thereof. The inner end portion of each arm 34 is of lesser height than the slot in its related block 35. Accordingly, each arm 34 is rockable in a vertical plane about its fulcrum pin 45.

Threaded through the bottom of each block 35 is a pair of screws 46, 46, one disposed forwardly and the other rearwardly with respect to the fulcrum pin 45. These screws hold the inner end portion of the arm 34 in an elevated position relative to the block 35 and against the fulcrum pin 45. By adjustments of said screws the locking arm 34 obviously may be rocked in a vertical plane about the fulcrum pin 45 to elevate or lower the forward end portion of said locking arm relative to the block 13 and the armature 5. The screws 46 are provided with lock nuts 47 to maintain desired adjustments of said screws.

As will be apparent, the blocks 34 may be mounted directly upon the armatures 5 instead of upon blocks, such as the blocks 13, fastened to said armatures.

Obviously, the blocks 35 may readily and easily be mounted on the blocks 13 by the yoke elements 36. Obviously, too, very accurate adjustments of the arms 34 may easily be effected by the adjusting screws 46, and may be maintained by the lock nuts 47.

Enclosing the mechanisms beneath the panel

is a base structure 48 which serves as a support for said panel.

Without further description it is thought that the features and advantages of the invention will be readily apparent to those skilled in the art, and it will, of course, be understood that changes in the form, proportion and minor details of construction may be resorted to, without departing from the spirit of the invention and scope of the appended claims. 10

I claim:

1. An interlocking relay comprising a pair of electro-magnets, an armature related to each electro-magnet and disposed to be lifted when its related electro-magnet is energized and to drop when its related electro-magnet is deenergized, a switch arm carried by each armature, a back contact related to each switch arm, each switch arm being arranged to engage its back contact when the related armature drops and to be disengaged from its back contact when the related armature is lifted, a locking arm carried by each armature to be lifted and to drop in harmony therewith, a pair of locking dogs, one related to each locking arm and each pivoted for swinging movement toward and away from the other, means tending constantly to swing each locking dog toward the other, means whereby said locking arms are effective, when lifted by their armatures, to hold said locking dogs, in outwardly swung positions relative to each other, a toe on each locking dog disposed in the path of dropping movement of the related locking arm as long as the locking dog remains in an outwardly swung position and effective, when engaged by the related locking arm, to stop dropping of the related armature prior to engagement of the switch arm thereof with its related back contact, said locking dogs being so disposed relative to each other that when either is held in its outwardly swung position by its related locking arm the other, when released by its locking arm, is free to swing inwardly sufficiently to withdraw its toe from the path of dropping movement of the related locking arm, thereby to permit sufficient dropping of the related armature to engage its switch arm with its related back contact, said locking dogs further being so disposed relative to each other that when either is in a released, inwardly swung position it serves to prevent inward swinging of the other, whereby, when the locking arm related to the latter locking dog drops, it is intercepted by the toe of the latter locking dog. 40

2. An interlocking relay as set forth in claim 1 in which the means tending constantly to swing the locking dogs toward each other comprises counterweights carried by the dogs. 45

3. An interlocking relay as set forth in claim 1 in which the means tending constantly to swing the locking dogs toward each other comprises a spring. 60

4. An interlocking relay as set forth in claim 1 in which the means tending constantly to swing the locking dogs toward each other comprises counterweights carried by the dogs and a cooperating spring. 65

5. An interlocking relay comprising a pair of electro-magnets, an armature related to each electro-magnet and disposed to be lifted when its related electro-magnet is energized and to drop when its related electro-magnet is deenergized, a switch arm carried by each armature, a back contact related to each switch arm, each switch arm being arranged to engage its back contact 70

when the related armature drops and to be disengaged from its back contact when the related armature is lifted, a locking arm extending forwardly from each armature to be lifted and to drop in harmony therewith, a pair of locking dogs, one related to each locking arm and each pivoted for swinging movement toward and away from the other in a plane at right angles to the plane of movement of the related locking arm, means tending constantly to swing each locking dog inwardly toward the other, each locking dog including an outwardly extending arm overlying the forward end portion of the related locking arm to be engaged and lifted by the latter when same is lifted, thereby to releasably hold the locking dog in an outwardly swung position, a toe on each locking dog underlying the related locking arm as long as the locking dog remains in an outwardly swung position and effective, when engaged by the related locking arm to stop dropping of the related armature prior to engagement of the switch arm thereof with its related back contact, said locking dogs being so disposed relative to each other that when either is held in its outwardly swung position by its related locking arm the other, when released by its locking arm, is free to swing inwardly sufficiently to withdraw its toe from the path of dropping movement of the related locking arm, thereby to permit sufficient dropping of the related armature to engage its switch arm with its related back contact, said locking dogs further being so disposed relative to each other that when either is in a released, inwardly swung position it serves to pre-

vent inward swinging of the other, whereby, when the locking arm related to the latter locking dog drops, it is intercepted by the toe of the latter locking dog.

6. An interlocking relay as set forth in claim 1 in which the toe of each locking dog is provided with a nib for engagement with the related locking arm when the latter is resting upon the toe to prevent inward swinging movement of the related locking arm regardless of the disposition of the other locking dog.

7. An interlocking relay as set forth in claim 5 including means mounting each locking arm on its related armature for adjustable rocking movement in the plane of the arm, thereby to permit accurate predetermining positioning of the forward end portion of each locking arm relative to its related locking dog, and means for rockably adjusting said arm and for maintaining adjustments thereof.

8. An interlocking relay as set forth in claim 5 including a block mounted on each armature, each block having a slot accommodating the rear end portion of the related locking arm, a fulcrum element carried by each block against which the related locking arm is seated for rocking movement in the plane thereof, and a pair of adjusting screws carried by said block, one forwardly and other rearwardly of said fulcrum element, for cooperation with said locking arm to maintain same engaged with said fulcrum element and to adjust same in the plane thereof relative to said block.

FREDERICK T. FEREDAY.
